UNITED STATES PATENT OFFICE.

ALBERT KOMP, OF NEW YORK, N. Y.

BRONZING-MACHINE.

SPECIFICATION forming part of Letters Patent No. 247,660, dated September 27, 1881.

Application filed August 26, 1881. (No model.)

To all whom it may concern:

Be it known that I, ALBERT KOMP, a citizen of the United States, residing at New York, in the county and State of New York, have invented new and useful Improvements in Bronzing-Machines, of which the following is a specification.

This invention relates especially to that class of bronzing-machines wherein the freshly-printed sheet is placed on an endless carrier, and having been supplied with bronze-powder is subjected to the action of distributing devices co-operating with the sheet-carrier; and it consists in certain novel combinations of parts, hereinafter fully described.

This invention is illustrated in the accompanying drawings, in which Figure 1 represents a longitudinal vertical section. Fig. 2 is a plan or top view, omitting the reservoir and its concomitants. Fig. 3 is a side view. Fig. 4 is a like view, looking in an opposite direction to Fig. 3. Fig. 5 is a detail view of the griper. Fig. 6 is a plan or top view of the bucket-wheel.

Similar letters indicate corresponding parts. The letter A designates the endless sheet-carrier, composed in this example of an india-rubber apron, and supported by rollers B, the same having also combined therewith a cleaning-brush, B'. Above this sheet-carrier is located an endless griper-carrier, C, composed of two chains, which are connected together by a traverse, D, forming the griper, and supported by chain-wheels E. This griper D is a strip of sheet metal bent over bars a, Fig. 5, constituting pivots of the carrier-chains C, to a zigzag shape, and it is so arranged relatively to the sheet-carrier A as to come in contact therewith in the movements of the carriers—that is to say, the bights of the strip between the bars are brought in contact with the face of the sheet-carrier. The griper D, however, can also be made flat, or of any other desired shape, and, if deemed expedient, additional gripers may be used, while the griper-carrier, moreover, may be formed of bands or an apron. Above and at the opposite ends of the sheet-carrier A are rollers F G—one a receiving-roller and the other a delivery-roller—these rollers terminating intermediate or inside of the carrier-chains C, and being fixed to the shafts of the chain-wheels E. In order to avoid injury

to the face of the sheet acted on by the receiving and delivery rollers F G, they are covered with fur or other similar material.

Intermediate of the receiving and delivery rollers F G are brushes H I, forming the bronze-distributing devices, these brushes being faced with fur or other similar material, and arranged in superficial contact with the sheet-carrier A. The brushes H have a revolving motion and brushes I a laterally-reciprocating motion, and in practice the brushes, as well as the rollers B F G, are made adjustable.

Below the upper or working portion of the sheet-carrier A is located a bed or support, J, and at a point opposite to each of the brushes H I in this bed are cavities b, or openings, leaving the sheet-carrier unsupported at those points, so that it is adapted to yield to the brushes, this being due also to the nature of the material composing the carrier. Next to the receiving-roller F, above the sheet-carrier A, is located a bronze-hopper, K, which has a vertically-reciprocating motion, but may also be left stationary, and which is supplied with bronze-powder from a reservoir, L, as herein-after more fully described.

The sheet to be bronzed is inserted between the receiving-roller F and the sheet-carrier A—namely, when the griper D reaches approximately that point—and the leading end of the sheet is seized by the griper, thus sharing the motion of the carriers, so that the printed face of the sheet is first covered with bronze dropping from the hopper K, then subjected to the action of the distributing-brushes H I, and finally discharged by the delivery roller G as it is released by the griper.

The operative parts of the machine are inclosed in a box, N, having a drawer, O, in the bottom thereof, serving to catch the surplus bronze.

In the bronze-reservoir L revolves a bucket-wheel, P, the buckets Q of which are hung on shafts d and weighted, as at e, so that they have a tendency to assume an upright position. To the shaft D of the buckets respectively is fixed a pinion, f, Figs. 4 and 6, and as the bucket-wheel revolves these pinions successively travel over a fixed toothed segment, S, making a complete revolution, whereby the buckets are reversed and emptied. The bucket-wheel P is so arranged in the bronze-reservoir

that its buckets may empty over the edge thereof, and the toothed segment S is placed in such a position that when the buckets Q are reversed by its means they are above the bronze-hopper K, thus emptying into the latter. The buckets Q, however, can also be left stationary on the wheel. The toothed segment S is a fixture of the machine-frame.

Motion is given to the revolving brushes H by a belt, T, (see Fig. 4,) from the shaft B' of one of the sheet-carrier rollers, this shaft containing also a driving-pulley, U, while motion is imparted to the laterally-reciprocating brushes I by a lever, V, connected to the pitman of an eccentric, W, the latter being placed loosely on the shaft F' of the sheet-receiving roller, and being geared with the shaft B' of the adjacent sheet-carrier roller by cog-wheels g. (Best seen in Fig. 3.) The reciprocating brushes I are guided in their motions by means of rods o. The shaft B' transmits motion to the shaft F' by cog-wheels h, and it also carries trip-wheels i, one at each end, acting on slide-rods j, which are bifurcated at the upper end for the reception of gudgeons l, projecting from the bronze-hopper K, so that the latter receives its motion from that source. The bucket-wheel P receives its motion from an eccentric, X, on the shaft F' of the sheet-receiving roller through a pawl, n, which is pivoted to the pitman of such eccentric, and acts on a ratchet-wheel, Y, fixed to the bucket-wheel shaft. Any other suitable driving mechanism, however, may be substituted for that described without departure from my invention.

The hopper K is a bronze-feeder, and in lieu thereof I can use a roller covered with fur or other similar material, or a chute, or any other of the devices generally employed for a similar purpose.

What I claim as new, and desire to secure by Letters Patent, is—

1. The combination, substantially as herein-before described, of the endless sheet-carrier and the endless griper-carrier having its griper arranged to be brought into superficial contact with the sheet-carrier.

2. The combination, substantially as herein-before set forth, of the endless sheet-carrier, the endless griper-carrier having its griper arranged to come in contact with the sheet-carrier, and the bronze-distributing devices co-operating with the sheet-carrier.

3. The combination, substantially as herein-before set forth, of the endless sheet-carrier, the endless griper-carrier having its griper arranged to come in contact with the sheet-carrier, the bronze-feeder, and the bronze-dis-

tributing devices co-operating with the sheet-carrier.

4. The combination, substantially as herein-before set forth, of the endless sheet-carrier, the endless griper-carrier having its griper arranged to come in contact with the sheet-carrier, and the sheet-receiving roller.

5. The combination, substantially as herein-before set forth, of the endless sheet-carrier, the endless griper-carrier having its griper arranged to come in contact with the sheet-carrier, and the sheet-delivery roller.

6. The combination, substantially as herein-before set forth, of the endless sheet-carrier, the endless griper-carrier having its griper arranged to come in contact with the sheet-carrier, the sheet-receiving roller, and the sheet-delivery roller.

7. The combination, substantially as herein-before set forth, of the endless sheet-carrier, the endless griper-carrier having its griper arranged to come in contact with the sheet-carrier, the bronze-hopper, the bronze-distributing devices, the sheet-receiving roller, and the sheet-delivery roller.

8. The combination, substantially as herein-before set forth, of the endless sheet-carrier, composed of an india-rubber apron, the bronze-distributing brushes arranged in superficial contact with the sheet-carrier, and the bed or support for the upper portion of the sheet-carrier, having cavities or openings opposite to the brushes, allowing the sheet-carrier to yield thereto.

9. The combination, substantially as herein-before set forth, of the sheet-carrier, the bronze-feeder arranged above the sheet-carrier, the bronze-reservoir, and the revolving bucket-wheel of the bronze-reservoir, having its buckets arranged to supply the bronze-feeder.

10. The combination, substantially as herein-before set forth, of the sheet-carrier, the bronze-feeder arranged above the sheet-carrier, the bronze-reservoir, the revolving bucket-wheel of the bronze-reservoir, having its buckets hung and weighted to assume an upright position, the pinions fixed to the shafts of the buckets, respectively, and the fixed toothed segment engaging the pinions successively for reversing and emptying the buckets at a point above the bronze-feeder.

In testimony whereof I have hereunto set my hand and seal in the presence of two subscribing witnesses.

A. KOMP. [L. S.]
